UNITED STATES PATENT OFFICE.

WILLIAM S. HIETT, OF TEMPLE, GEORGIA, ASSIGNOR OF ONE-FOURTH TO CARRIE HUTCHESON, ONE-FOURTH TO WILLARD D. HUTCHESON, AND ONE-FOURTH TO JOSEPH F. HUTCHESON, ALL OF TEMPLE, GEORGIA.

PLOWSTOCK.

Application filed May 20, 1921. Serial No. 471,054.

To all whom it may concern:

Be it known that I, WILLIAM S. HIETT, residing at Temple, in the county of Carroll and State of Georgia, have invented new and 5 useful Improvements in Plowstocks, of which the following is a specification.

This invention relates to plows, and has for one of its objects the provision of means for reinforcing the plow beam to provide for 10 a uniformity of strength with a minimum of weight.

Another object of importance resides in 15 a construction which provides a very minute adjustment of the plow carrier, the latter being susceptible of adjustment without in any way disturbing the reinforcing elements to weaken the construction.

A further object of the invention resides 20 in a construction of a depth gauge which can be very easily and conveniently adjusted as the occasion requires.

The nature and advantages of the invention will be better understood when the following detailed description is read in connection with the accompanying drawings, 25 the invention residing in the combination, construction, and arrangement of parts as claimed.

In the drawings forming part of this application, like numerals of reference indicate 30 the similar parts in the several views and wherein:—

Figure 1—is a side elevation.

Figure 2—is a detail view of the plow 35 carrier.

Figure 3—is a detail view of the reinforcing elements.

Figure 4—is a top plan view.

Figure 5—is a sectional view taken on 40 line 5—5 of Figure 1.

Figure 6—is a detail view of the plow beam.

Figure 7—is a similar view of the clamping means for associating the depth gauge 45 with the plow carrier.

Figure 8—is a detail view of the depth gauge.

Referring to the drawings in detail, 10 indicates the plow beam of usual construction and to one end of which is secured the plow 50 handles 11. Secured to the opposed sides of the plow beam 10 are metallic straps 12 shaped to conform to the bottom portion of the stock as shown and of a suitable length to

afford the beam maximum strength and 55 durability. Each strap 12 projects beyond the lower edge of the beam as at 13 and is then offset inwardly as at 14, the corresponding terminals or offset portions 14 being arranged in parallelism and secured together 60 by means of a bolt or other suitable fastening element 15. By reason of this construction, the straps 12 constitute a support for the foot or plow carrier to be presently described. Embracing the upper edge of the 65 beam 10 is a yoke 16 having its terminal arranged against the straps 12 and secured thereto by one of the fastening elements 17 utilized to secure the straps 12 to the beam 10. The yoke 16 is of suitable size and 70 strength to bear the downward thrust of the beam 10 and straps 12 at its point of connection with said parts as shown.

The foot or plow carrier embodies two identically constructed members 18 and 19 75 respectively, each being substantially Z-shaped with their corresponding upper extremities 20 arranged against the opposed sides of the plow beam 10. The opposite or lower extremities of these members are beveled and are welded or otherwise suitably secured together by means of a plug 21 arranged between said members. The members 18 and 19 are offset inwardly as at 22 immediately beneath the plow beam 10 to 80 bring said members closer together, the intermediate or horizontal portion 23 of said members being secured to the parallel extremities 14 of the straps 12 by means of the fastening element 15. The openings 24 in 85 the beam do not register with all of the respective parts which are so closely related that a very minute adjustment of the plow carrier may be made in order to adjust the plow carrier to vary its position with relation to the ground as the occasion requires. Consequently, the fastening element 26 is adapted to be received by the respective openings 24 and 25 as the occasion requires. Manifestly, the construction and arrangement 90 of parts is such that the plow foot or carrier can be very easily and minutely adjusted to vary the position of the plow proper with relation to the ground, without changing or disturbing in any way the reinforcing elements therefore making it possible to make this adjustment with the weakening of the plow beam. The element also 100 105

provides a construction wherein the plow beam possesses maximum strength without unnecessary adding to the weight of the plow beam.

- 5 The depth gauge above referred to is clearly illustrated in Figure 8, and is adapted to be associated with the plow carrier through the instrumentality of a two-part clamp, the respective parts of which 10 are indicated at 28 and 29 respectively, and of substantially U-shaped formation to embrace the upper and lower edges of the horizontally disposed portion of the plow carrier as illustrated in Figures 1 and 5. Rising 15 from the part 29 of the clamp is a threaded element 30 which passes through an opening in the part 28 of the clamp, and by means of which the respective parts of the clamp are held operatively associated. 20 The bolt 30 passes between the members 18 and 19 of the plow carrier as clearly illustrated in Figure 5 and is adapted to receive a nut 30'. The lower part of the clamp 29 is formed to provide a depending plate 31 25 which is adapted to be embraced by the U-shaped portion 32 of the depth gauge 33. The plate 31 is provided with an elongated slot 31' with which the opening 34 in the depth gauge is adapted to register to receive 30 a fastening element 35 which holds the depth gauge associated with the plate 31, and at the same time permits the depth gauge to be adjusted as desired.

While it is believed that from the foregoing description the nature and advantages of the invention will be readily apparent, I desire to have it understood that I do not limit myself to what is herein shown and described, and that such changes may 40 be resorted to when desired as fall within the scope of what is claimed.

What I claim is:

1. In combination, a plow beam, reinforcing elements secured to the opposite sides 45 of the said beam and having their corre-

sponding lower extremities depending beneath the beam in parallelism, a plow carrier including spaced members having corresponding upper ends embracing and adjustably associated with the plow beam, said members being at the opposite sides of the parallel extremities of the reinforcing elements and secured thereto, and a depth gauge supported by said members of the plow carrier.

2. In combination, a plow beam, reinforcing elements secured to the opposite sides of the plow beam and having the corresponding extremities offset inwardly and depending from said beam, a plow carrier comprising spaced members having their upper ends adjustably secured to the opposite sides of the plow beam, said members being arranged at the opposite sides of said extremities of the reinforcing elements and secured thereto, a two-part clamp embracing the upper end and lower edges of the said members at a point rearwardly of the reinforcing elements, an adjustable connection between the respective parts of the clamp, and a depth gauge adjustably mounted upon the lowermost part of said clamp for the purpose specified.

3. In combination, a plow beam, reinforcing elements secured to the opposite sides 75 of the beam, a plow carrier comprising spaced members secured to said beam and also to the reinforcing elements, a two-part clamp embracing the upper and lower edges 80 of said members rearwardly of said reinforcing elements, an adjustable connection between the respective parts of the clamp, a slotted plate depending from one part of the clamp, a depth gauge slidably mounted on said plate, and a fastening element carried 85 by said gauge and passed through said slot for holding the depth gauge in a given position.

In testimony whereof I affix my signature.

WILLIAM S. HIETT.
